UNITED STATES PATENT OFFICE.

JOHN C. DAVIS, OF NEOSHO, MISSOURI.

WASHING-MACHINE.

SPECIFICATION forming part of Letters Patent No. 670,852, dated March 26, 1901.

Application filed May 21, 1900. Serial No. 17,463. (No model.)

To all whom it may concern:

Be it known that I, JOHN C. DAVIS, a citizen of the United States, residing at Neosho, in the county of Newton and State of Missouri, have invented new and useful Improvements in Washing-Machines, of which the following is a specification.

My invention relates to improvements in washing-machines, and pertains to a machine constructed to produce a double rubbing and pressing action, all of which will be fully described hereinafter and particularly pointed out in the claims.

The primary object of my invention is to provide a washing-machine in which the tub or box portion is provided with a rubbing-surface or washboard and in which there is a vertically-movable cover having a similar concaved washboard or surface and a vertically-movable cylinder situated within the tub and between the two washboards and to which the goods to be washed may be clamped and held in the desired position against being misplaced, whereby a combined double rubbing and pressing action may be produced and whereby the machine is adapted for washing small or large articles and also adapted for washing small or large quantities of clothes during a single operation.

In the accompanying drawings, Figure 1 is a vertical longitudinal sectional view of a washing-machine embodying my invention. Fig. 2 is a perspective view with the top removed. Fig. 3 is a top plan view with the top removed. Fig. 4 is a side elevation with the top in position thereon. Fig. 5 is a perspective view of the hooks carried by the cover.

Referring now to the drawings, A indicates an oblong box or tub, which is preferably formed of wood and in any suitable manner to effect a water-tight and durable construction, though it may be constructed of galvanized metal or other suitable material. Situated in the bottom of this box A is a washboard or corrugated rubbing-surface B, which is concaved, as shown, sufficiently to cause practically the whole of the rubbing-surface to be utilized in the washing operation. This rubbing-surface or washboard B is shorter than the box A and located at one end por-

tion thereof, as illustrated, whereby a space C is provided of sufficient size to accommodate one washing of clothes where they may be placed and soaked prior to their being attached to the washing-cylinder D.

Projecting from the sides of the box A and at points intermediate the ends of the washboard or surface B are arms E, which are provided with vertically-elongated slots F. These slots F are adapted to receive the journals or bearings of an angular cylinder-shaft G, and situated also in these slots F are bearing-blocks a, upon which the lower ends of suitable coil-springs b rest, the upper ends of the said coil-springs bearing against the blocks a', which are held in position by removable bolts or members c, which are situated at the upper ends of the slots F. The cylinder is comprised of a plurality (preferably three) disks H, which are secured to the shaft G in any suitable manner, and connecting their peripheries are the slats I, which extend longitudinal the cylinder-shaft and which, as will be hereinafter described, serve in connection with other members as means for clamping the goods or garments to be washed. The disks H are provided with a plurality of water passage-ways g, which are for the purpose of enabling the free passage of the water within and without the spaces between the outer and inner disks H in a manner which will be more fully explained hereinafter.

Situated upon and secured to the angular shaft G at points just outside of the end disks H of the washing-cylinder D are a plurality of laterally-extending longitudinally-slotted arms J, the said arms being preferably carried by thimbles K, which receive the said shaft G and are secured thereto in any suitable manner. These arms J are provided with a plurality of transversely-arranged and longitudinally-extending series of bolt or pin openings d, adapted to receive the pins e. The ends of these arms J are located in a line with the space between the pairs of slats I, whereby the essentially U-shaped clamping wires or rods L are adapted to pass longitudinally over the cylinder between the said slats for clamping the garments to be washed and to have their outturned ends f inserted

within the slots of the longitudinally-slotted arms J and to be held therein by means of the pins e, which may be inserted in any one of the holes in the said arms, according to the 5 character and quantity of garments that it is desired to clamp to the cylinder. There may be provided any desired number of these clamping members; but I here show four, which I deem sufficient to hold the garments 10 firmly in position upon the cylinder for the washing action.

The upper rubbing and pressing surface to coact with the upper side of the cylinder is situated within the top or cover N and consists of a concaved rubbing or corrugated surface P, made of any desired or suitable material. The lower edges of the sides of this cover N are adapted to rest upon the upper edges of the sides of the box A, and the sides 15 are provided with vertically-elongated centrally-arranged slots Q, which provide slots to permit the free vertical movement of the shaft of the cylinder D under the pressure of the washing operation. This cover N is held 20 in position and permitted to have a free vertical movement by the vertically - arranged rods i, made, preferably, of galvanized material and extending upwardly from the upper edges of the sides of the box A. There are 25 preferably four of these rods, and they pass into vertically-elongated openings m, formed in the sides of the cover N, and by means of which the cover is permitted to freely vibrate vertically under pressure of the washing of 30 the garments.

For the purpose of adding additional pressure to the weight of the cover N, I provide four springs S, which have their lower ends connected to suitable members T, attached 35 to the sides of the box A, and their upper ends provided with hooks n, adapted to engage the notches p of the members q, which are attached to the sides of the cover N. There will be four of these springs, and their 40 tension is adjustable through the medium of the notched members q, and they are readily detached from these members for the purpose of permitting the removal of the cover N.

The box A is provided with the depending 45 legs 1 and 2, the two situated at the rear end being provided with suitable casters or wheels 3, and the opposite end of the box A is provided with projecting handles 4, by means of which the washing-machine may be rolled 50 around, as a wheelbarrow. The rear end of the box A is provided with an outlet-spigot 5, by means of which the box may be emptied of the water therein, and this is facilitated by lifting the front end of the box through 55 the medium of the handles 4. By means of this arrangement the machine can be rolled to any desired point for the purpose of emptying the water therefrom instead of transporting the water in buckets, which is very 60 laborious.

Situated at the under side of the front end of the box A is a sliding tub-support 6, adapt-

ed to be drawn outward and adapted to support a tub or tubs.

The rubbing-surface B, situated in the bottom of the box A, is loose and adapted to be removed therefrom, it being held in position against movement under the rubbing operation through the medium of the cleats or projections 7, which straddle longitudinal strips 75 8, arranged in each side of the bottom of the box. The cylinder D can also be removed by the removal of the pins c at the upper ends of the slots F, and the cover is removed, as before stated, by unhooking its spring, 80 thus leaving a box A, which is entirely clear and free of all of the washing apparatus and enabling it to be thoroughly cleansed when desired.

In some instances it may not be desirable 85 to use the springs either in connection with the shaft of the cylinder D or in connection with the cover N, and when not deemed necessary for the purpose of increasing the pressure of the washing operation these may be 90 thrown out of operation by unhooking the springs from the cover and by removing the springs b from the slots F, in the manner before explained.

In the operation of this machine the clothes 95 or garments to be washed are clamped to the cylinder D, in the manner before described, and with those portions of the garments which need the greatest amount of washing held in the position to receive the rubbing 100 and pressing action, which is very instrumental and effective in enabling me to thoroughly wash the wristbands and neckbands, collars, and cuffs of garments. The cylinder 105 D is permitted to have a free vertical movement under the pressure of the clothes and according to the nature and quantity of the garments being washed, and the cover N is vertically movable in respect to the cylinder D, whereby the several parts which combine 110 to effect the pressing and rubbing action are permitted to have free relative movement. In the washing operation the water which is 115 pressed from the garments as the cylinder is being revolved and carried between the disks E will pass therefrom through the passages made therein and fresh water will pass therein through the same passages, thus enabling me to effect a free circulation of the water to both sides of the garments that are being 120 washed.

A machine of the character shown and described is very effective in its operation and is adapted to wash a single small article, a number of small articles, or a large article or 125 a number of large articles.

Having thus described my invention, what I claim, and desire to secure by Letters Patent, is—

1. A washing-machine comprising a water-chamber having in its bottom a stationary 130 concaved rubbing and pressing surface, a cover having its inner upper side provided with a concaved rubbing and pressing sur-

- face, a vertically-movable washing-cylinder situated between the rubbing-surfaces, the washing-chamber and the cover being provided respectively with vertically-arranged guiding and holding rods and openings for the said rods, substantially as described.
2. A washing-machine comprising a shaft, a cylinder carried by the shaft, radially-projecting longitudinally-slotted arms situated at opposite ends of the cylinder, transverse pins passing through the slotted arms, and essentially U-shaped clamping-rod passing longitudinal the cylinder having laterally-turned ends adapted to pass through the slots of the slotted arms and engage said pins, substantially as described.
3. In a washing-machine, the combination with a receptacle having a stationary scrubbing-surface therein, of a normally downwardly-held vertically-movable scrubbing-cylinder, and a normally downwardly-retained vertically-movable cover carrying a scrubbing-surface therein, substantially as described.
4. In a washing-machine the combination with a receptacle having a stationary scrubbing-surface therein, of a spring-pressed vertically-movable scrubbing-cylinder and a spring-retained vertically-movable cover car-
- rying a scrubbing-surface therein, substantially as described.
5. A washing-machine comprising a receptacle, a vertically-movable cylinder mounted therein, vertically-arranged guiding and holding rods carried by the receptacle and a cover carrying a rubbing-surface and vertically-arranged rod-receiving openings, substantially as described.
6. A washing-cylinder comprising a shaft, disks mounted thereon and having openings therein, longitudinally-extending bars arranged in pairs connecting said disks, outwardly-extending arms carried by the shaft and having longitudinally-arranged slots and transverse bolt-receiving openings, bolts in said openings and U-shaped clamping-rod adapted to rest between the longitudinally-arranged bars and having laterally-turned ends, adapted to enter the slots and engage the transverse bolts, substantially as described.

In testimony whereof I have hereunto set my hand in the presence of two subscribing witnesses.

JOHN C. DAVIS.
